COIN PURSES AND PURSE COMBINATIONS

Dana B. Collings, Springfield, Mass., assignor to Buxton, Incorporated, Springfield, Mass., a corporation of Massachusetts

Application May 25, 1953, Serial No. 357,156

9 Claims. (Cl. 150—37)

This invention relates to an improvement in purses and similar containers for coins, bus tokens and the like, and the combination of such purses with other receptacles such as billfolds, wallets, pocket cases, handbags and the like.

The principal object of the invention is the provision of an improved construction which, in addition to the normal purse closure which permits the insertion or removal of coins from the purse when the closure is opened, provides an auxiliary entrance to the purse through which coins may be inserted when the closure is closed but which prevents escape of the coins through said entrance.

A further object is to provide a structure having the above advantages and which is applicable to a wide range of receptacles and which is particularly adaptable to combination receptacles which provide carrying capacity for other articles, such as bills and cards, as well as coins.

A further object is to provide a structure, which while preventing escape of the coins through the entrance slot does not materially interfere with the free movement of coins within the purse and which will not hinder or interfere with the removal of coins in the usual way when the purse closure is open.

Other and further objects and advantages residing in the details of construction will be made apparent in the disclosure of the accompanying drawing and in the following specification and claims.

In the accompanying drawing, which illustrates the invention as applied to a purse billfold combination:

Fig. 1 is a front view of a billfold and purse combination embodying the invention;

Fig. 2 is a sectional view substantially on line 2—2 of Fig. 1 and on a larger scale;

Fig. 3 is a fragmentary view showing the purse of Fig. 1 open and with parts broken away;

Fig. 4 is a view similar to Fig. 2 showing the manner of inserting a coin in the purse when the purse is closed;

Fig. 5 is a view similar to Fig. 3 but showing an alternative construction;

Fig. 6 is a top plan view of a billfold and purse combination in which the purse opens at the end of the billfold, parts being broken away;

Fig. 7 is a fragmentary detail sectional view showing the invention embodied in a purse as a separate entity, in which the bar member extends inwardly from the wall of the purse at the side of the slot opposite the closure flap;

Fig. 8 is a detail view of a member forming a wall portion and closure flap for the purse;

Fig. 9 is a fragmentary detail view showing the manner of forming a bar member in a compartment wall for cooperation with the member of Fig. 8 to form an alternative structure;

Fig. 10 is a fragmentary perspective view showing the structure formed by the members of Figs. 8 and 9; and

2

Fig. 11 is a view similar to Fig. 10 but showing a modified arrangement.

Referring to Figs. 1, 2 and 3, which show the invention applied to a billfold purse combination, the rear wall 5 of the billfold is shown as comprising a length of leather, plastic or other suitable material 1, and the front wall is shown as comprising spaced panel members 2 and 3 having flap extensions along their upper edges which, as shown at 4 in Fig. 2, are folded inwardly and downwardly over a stay or intermediate wall member 5 which fills the space between the panels 2 and 3. The adjacent end and bottom edges of the rear wall and panel members are connected together in any usual or desired manner to form the bill compartment of the billfold, and the spaces between the panel members 2 and 3 and wall member 5 provide the usual compartments for cards and the like.

Secured to the outer surface of panel 3 is a purse generally indicated at 6 which as shown in Figs. 2 and 3 comprises a back wall 7 from the upper edge of which extends a closure flap 8. From the side edges of the wall 7 extend inwardly folded generally triangular gussets 9. The front wall 10, which is shown as an extension from the lower edge of the rear wall, is folded upwardly and cemented, stitched or otherwise secured to the inturned forward skived edges 11 of the gussets. A conventional snap fastener 12 releasably secures the closure flap 8 to the front wall of the purse to close the purse.

As shown in Fig. 3 the rear wall of the purse is shown as stitched around its edge portions to the panel 3 by a line of stitching 14. The rear wall of the purse is provided with an elongated opening 15 positioned slightly below the upper edge of the rear wall. The line of stitching 14 where it extends across the top portion of the rear wall 7 is inclined downwardly, as at 16, from the upper corners and passes downwardly and along the sides and bottom of the opening, thus affording access to the interior of the purse through opening 15. Preferably, and as shown, the rear wall is provided with short slits or cuts 18 extending upwardly from the ends of opening 15 forming a shallow lip 19.

A substantially rigid, elongated guide and guard bar member 20 is carried by the panel member 3 and extends through opening 15, with the sides of the bar closely adjacent the edges of opening 15 and the free edge of lip 19, the portion of opening 15 above the bar forming a coin slot 21. As shown in Figs. 2 and 4 the bar 20 is generally triangular in cross section and is formed by embossing or pressure stamping from the material of the panel.

By the construction above described a coin, bus token or similar article can be inserted in the purse through the portion of opening 15, above the bar 20, as indicated at 22 in Fig. 4. The lip 19 and adjacent portion of the rear wall of the purse yield inwardly to admit the coin, the inclined portions 16 of the stitching acting as a funnel to guide the coin to slot 21. The inclined faces of bar 20 serve to guide the coin through the slot 21 and once the coin is in the purse to fend the coins in the purse away from the slot in the free movement of the coins in the purse, even when the purse is turned bottom side up. The bar 20 need extend inwardly only slightly beyond the inner face or surface of the rear wall of the purse to effectually prevent escape of the coins or similar articles from the purse. Where the flexibility of the material of the purse permits the slits 18 may be omitted and the extent of the slits 18 when employed affords control of the ease with which a coin can be introduced into the purse through the slot, whether or not relatively stiff or more flexible material is used in making the purse or its associated receptacle. Even when slits 18 are of substantial length the lip 19 tends to hug the

panel wall 3 when the purse closure flap 8 is closed due to the leverage imposed by the relatively sharp folding of the flap over the top of the purse, the inherent tendency of the material to straighten pressing the lip 19 outwardly against the adjacent surface of the panel 3. In general, the use of cuts 18 and the resulting lip 19 are preferable since it affords substantial closure of the coin slot opening above the bar 20 and increases the ease with which coins may be inserted.

A modified structure is shown in Fig. 5 in which the purse closure flap 25 and the adjacent portion of the purse wall is formed as a separate piece and the panel 3 of the billfold, or other associated receptacle, forms the major part at least of the rear wall of the purse, the lower edge portion of flap piece 25 forming only the upper edge portion of the rear wall where it merges into the flap. As shown in Fig. 5 the front wall 26 of the purse is provided along its lower edge with an inturned margin 27 which is stitched to panel 3 as at 28, and is provided along its side edges with gusset forming extensions 29 which are interlocked in a known manner as at 30 to the panel 3. The panel 3 is provided with the bar 20 as previously described. The closure flap 25 is stitched at the outer portions of its lower edge to the panel 3 by downwardly inclined lines of stitching 31. Intermediate the lines of stitching 31 the lower edge of flap 25 is provided with spaced vertical cuts or slits 32 forming a lip 33, the free edge of which lies along or closely adjacent the upper edge of bar 20. As will be apparent the structure of Fig. 1 functions in an identical manner with that previously described.

In Fig. 6 the invention is shown embodied in a different type of billfold-purse combination in which the purse opens at the end of the billfold and the coin and bill compartments overlap. In Fig. 6, which shows the billfold folded, the billfold is shown as comprising two lengths of material respectively forming the inner and outer walls 35 and 36 of the bill compartment 37. One end of the wall member 35 is extended to form a purse closure flap 38 and a short wall member 39 is secured at its outer end to the adjacent end of wall 36 as indicated at 40. The inner end of wall 39 is secured as indicated at 41 to wall member 35 and the side edges of wall member 39 are connected to the adjacent edge portions of wall 35 by gussets 42 to form a purse. Flap 38 and wall 36 are respectively provided with elements of a snap fastener 43 and 44 by which the closure flap 38 may be releasably secured in purse closing position.

The opposite ends of wall members 35 and 36 are secured together as at 45. A strap member 46 has one end portion 47 secured along its side and end edges, as by stitching not shown, to the outer face of wall member 35 and the free end of the strap is releasably secured, by a snap fastener 48, to wall member 36 to releasably retain the purse-billfold in the folded condition shown in Fig. 6. The present invention is incorporated in the receptacle combination of Fig. 6 by providing the wall member 35 adjacent flap 38 with an opening 49 and a lip 50 similar in all respects to opening 15 and lip 19 previously described. A rigid bar 51 is secured to strap 46 and extends through the opening. The bar 51 as shown is semi-circular in cross section presenting upper and lower surfaces converging inwardly of the purse. Bar 51 may be formed of plastic, metal or other suitable material. As will be apparent, when purse closure flap 38 is closed, coins, but tokens or the like may be introduced into the purse, without opening the closure 38, by inserting them between the strap 47 and the rear wall of the purse where they engage bar 51 and are cammed or directed inwardly beneath lip 50 by the surface of the bar.

In Fig. 7 the invention is shown applied to a purse which is formed as an entity in itself. As there shown the purse comprises a rear wall 52 with the usual closure flap extension 53, and a front wall 54 connected to the rear wall by side gussets 55. The rear wall is provided with a coin

slot opening 56 with a free lip 57, similar to the lips previously described. Below opening 56, parallel therewith and having its upper edge substantially coinciding with the lower edge of the opening, a rigid bar 58, triangular in cross section is secured by cement or any suitable means to the rear wall of the purse. As will be apparent coins or the like inserted through slot 56 will be guided into the purse by the upper inclined surface of the bar and that the converging inclined surfaces of the bar fend coins, once in the purse, from the slot and prevent their escape there-through.

The present invention provides a guarded slot construction easily applicable to a wide range of purse and other coin carrying receptacles and receptacle combinations. As will be apparent the guard bar need extend only slightly beyond the inner face of the purse wall to effectively prevent escape of the coins through the adjacent coin slot. The construction leaves the interior of the purse substantially unobstructed in its normal use, the bar offering no substantial obstruction to the removal of coins in the usual way. The structure and cross sectional shape of the bar may take various forms the essential requirement being that its dimensions and surface contour be such that it cams or directs the coins in the purse away from the entrance slot and the bar is so positioned relative to the slot as to effectuate that purpose.

Figs. 8, 9 and 10 show an alternative manner of forming the bar member in the billfold-purse combination of Fig. 5. In this alternative arrangement the flap-wall portion 60 is formed with an opening 61 below a lip 62. Instead of forming the bar member in the form of a ridge pressed outwardly from panel 3, as in Fig. 5, the panel 3 is cut as at 63 to form a shallow tongue 64. As shown in Figure 10 tongue 64 is inserted through opening 61 and the member 60 stitched to the panel 3 as at 65 with tongue 64 engaging the lower edge of opening 61 and bent thereby to extend stiffly into the purse, and act, in the manner previously described, to guide coins into the purse through the slot between lip 62 and tongue 64 and to fend coins from exit through the slot. The outer wall of the purse is omitted in Fig. 10 but it will be understood that outer wall and gusset members may be stitched or interlocked to panel 3 as in Fig. 5 to complete the structure.

In the modification shown in Fig. 11 the tongue 64 of Fig. 10 is replaced by a slightly deeper tongue 66 which is stitched as at 67 to the portion of member 60 below the opening 61 give rigidity to the bar formed by the tongue 64. This last structure is preferable where the parts are formed of thin leather or similar very flexible material.

What is claimed is:

1. In a receptacle having wall members forming a plurality of compartments, one of said compartments being a coin purse provided with a releasable closure, one wall of the purse being provided with an opening having a free edge, a bar member fixed to said receptacle and extending into said purse adjacent said free edge and forming with the latter a coin slot for the entrance of coins into the purse when said releasable closure is closed, the surface of said bar member adjacent said slot being inclined inwardly of the purse to guide coins into the purse, the portion of said bar within the purse acting to fend coins within the purse from exit through said slot.

2. In a receptacle having wall members forming a plurality of compartments, one of said compartments being a coin purse provided with a releasable closure, one wall of the purse being provided with an opening having a free edge, a substantially rigid bar member fixed to said receptacle and extending into said purse adjacent said free edge and forming with the latter a coin slot for the entrance of coins into the purse when said releasable closure is closed, the surface of said bar member adjacent said slot being inclined inwardly of the purse to guide coins into the purse, the portion of said bar within the purse having sloping sides to guide coins into the

purse and acting to fend coins within the purse from exit through said slot.

3. In a receptacle having a plurality of compartments, one of said compartments being a coin purse having a wall in part attached to a wall member of a second compartment of the receptacle, an unattached portion of said purse wall being formed with an opening having an edge free of attachment to said member, a bar member carried by said wall member and extending into said purse adjacent to said free edge and forming therewith a coin slot for the entrance of coins into the purse, the portion of said bar member within the purse acting to fend coins within the purse from exit through said slot.

4. In a receptacle having a plurality of compartments, one of said compartments being a coin purse having a wall in part attached to a wall member of a second compartment of the receptacle, an unattached portion of said purse wall being formed with an opening having an edge free of attachment to said member, a substantially rigid bar member carried by said wall member and extending into said purse adjacent to said free edge and forming therewith a coin slot for the entrance of coins into the purse, the portion of said bar member within the purse having sloping sides to guide coins into the purse and acting to fend coins within the purse from exit through said slot.

5. In a receptacle having a plurality of compartments, one of said compartments being a coin purse having a wall in part attached to a wall member of a second compartment of the receptacle, an unattached portion of said purse wall being formed with a shallow lip having a free edge, a bar member carried by said wall member and extending into said purse adjacent to said free edge and forming therewith a coin slot for the entrance of coins into the purse, the portion of said bar member within the purse acting to fend coins within the purse from exit through said slot, the face of said bar member adjacent said lip sloping inwardly from the free edge of the latter to guide coins into the slot.

6. A receptacle as in claim 5, said bar member comprising a ridge substantially triangular in cross section formed in the said wall member of said second compartment.

5 7. A receptacle as in claim 5, said bar member comprising a shallow tongue cut in the said wall of said second compartment.

10 8. A receptacle as in claim 5, said bar member comprising a tongue cut in the said wall of said second compartment, the edge portion of said tongue being stitched to the inner face of the purse wall adjacent the free edge of said lip.

9. In a receptacle having a plurality of compartments, one of said compartments being a coin purse formed by 15 a front wall member connected at three sides to a wall member of a second compartment of the receptacle, the fourth side being open to afford access to the interior of the purse, a flap secured in part to said second compartment wall member opposite the free edge of said front wall member and foldable thereover to close the purse, the unsecured portion of the flap including a free lip portion and forming, with the adjacent surface of 20 said second compartment wall member, a coin slot for entrance of coins into the purse, the free lip portion extending in a direction opposite to the direction of extension of the flap when the latter is in purse opening position, the material of the flap and lip having sufficient resistance to folding to press the lip against said second compartment wall member when the flap is folded to 25 purse closing position and thereby close said slot to prevent coins within the purse from exit through said slot.
